[57] CLAIM

The ornamental design of a ladder tool caddy, as shown and described.

DESCRIPTION

FIG. 1 is a perspective view of a ladder tool caddy showing our new design;

FIG. 2 is a rear elevation view thereof;

FIG. 3 is a top plan view thereof;

FIG. 4 is a front elevation view thereof;

FIG. 5 is a bottom plan view thereof;

FIG. 6 is a left side elevation view thereof; and

FIG. 7 is a right side elevation view thereof.

The phantom lines showing a ladder in FIG. 1 form no part of our design as claimed.
